FUNGICIDAL AND BACTERICIDAL COMPOSITIONS

Donald K. Ballman, Midland, Mich., assignor to
The Dow Chemical Company, Midland, Mich.,
a corporation of Michigan

No Drawing. Application December 26, 1941,
Serial No. 424,477

5 Claims. (Cl. 167—31)

The present invention is concerned with fungicidal and bactericidal compositions and particularly with such compositions comprising as an active toxicant a mixture of phenolates.

According to the present invention, it has been discovered that when alkali metal salts of pentachlorophenol and of 2-phenyl-monochlorophenol are mixed together, compositions are obtained which exert a fungicidal and bactericidal action greatly in excess of that predictable from a knowledge of the effectiveness of the component phenolates. The proportions of materials employed vary somewhat with the use for which the composition is designed and the particular salts concerned. Generally, from 10 to 100 parts by weight of the alkali metal salt of 2-phenyl-monochloro-phenol is used for each 100 parts of the alkali metal pentachlorophenolate.

The compositions of the invention may be prepared by grinding or otherwise mixing the 2-phenyl-monochlorophenolate and pentachlorophenolate to obtain finely-divided solid products adapted to be dissolved in water or other suitable liquid carrier. In an alternate procedure, a mixture of the free phenols may be treated with aqueous alkali to form liquid phenolate products adapted to be either evaporated to dryness and ground, or employed for a fungicidal and germicidal control as obtained or after modification with additional liquid diluent.

Mixtures of the sodium salts of pentachlorophenol and of 2-phenyl-monochloro-phenol constitute the preferred embodiment of the present invention, although other salts such as the potassium and lithium salts or mixtures of sodium, potassium, and lithium salts may be substituted therefor. The commonest form in which the 2-phenyl mono-chloro-phenolate is employed is as a mixture comprising from 70 to 80 per cent by weight of the ortho-chloro isomer and the balance principally the para-chloro isomer, with only a trace of the meta-chloro compound. This mixture is obtained by forming the alkali metal phenolate from the phenol mixture resulting from the direct chlorination of 2-phenyl-phenol. If desired, however, pure 2-phenyl-6-chlorophenolate, 2-phenyl-5-chloro-phenolate, or 2-phenyl-4-chloro-phenolate may be employed.

The phenolate mixtures have been found superior to either the pentachlorophenolates or 2-phenyl-monochlorophenolates alone as regards the fungicidal and bactericidal controls accomplished in such representative fields as the treatment of freshly sawn lumber for sap stain control, mold-proofing of canvas and other rough fabrics, preservation of cordage, etc. In such operations aqueous solutions comprising from about 4 to about 10 pounds of toxicant per 100 gallons (U. S.) are employed. The treatment of the wood or other organic product may be ac-

complished either by dipping or by pressure impregnation. In pressure impregnation of wood, the treatment also serves to protect the cellulosic structure from attack by termites.

5 Similarly, the phenolate mixtures have been found effective in the preservation of paper and specifically in the mold proofing of egg case flats and fillers. For this use from about 0.2 to 0.5 per cent by weight on a dry basis of the phenolate mixture is incorporated with the paper pulp during the beating step. The paper product made from the treated pulp is resistant to mold growth even under conditions of high humidity, and as in the case of egg flats and fillers, may exert a 10 desirable fungistatic effect upon food products wrapped or packed therein.

15 A further development in which the composition of the present invention has been found particularly effective is that of slime and algae control. From 2 to 10 parts of the phenolate mixture per million parts of water prevents the growth of algae and slime organisms in the water systems of paper mills, humidifier and boiler installations, cooling towers, etc. In such application a mixture of 60 per cent by weight pentachlorophenolate—40 per cent by weight 2-phenyl-monochloro-phenolate has been found particularly satisfactory.

20 The following examples illustrate the efficiency 30 of representative compositions falling within the scope of the invention but are not to be construed as limiting.

Example 1

35 A series of determinations were carried out to ascertain the effectiveness of a mixture of sodium pentachlorophenolate and sodium - 2 - phenyl-monochloro-phenolate (the ortho-para mixture) against a number of representative organisms. The particular product employed consisted of a 40 mechanical mixture of 60 parts by weight of the sodium pentachlorophenolate with 40 parts by weight of the 2-phenyl-monochloro-phenolate. Control determinations were made with sodium pentachlorophenolate alone. The following table 45 sets forth the results obtained in terms of parts by weight of toxicant per million parts of water required to kill the test organisms employed.

50	Organism	Parts per million to kill with—	
		Sodium pentachlorophenolate	Mixed phenolates
55	<i>Escherichia coli</i>	1,600	850
	<i>Aerobacter cloacae</i>	750	350
	<i>Aerobacter aerogenes</i>	1,150	650
	A species of <i>Oidium</i>	800	100
	A species of <i>Penicillium</i>	500	30
	A species of <i>Aspergillus</i>	900	60
60	A species of <i>Trichoderma</i>	850	60

Example 2

A mixture of 40 parts by weight of sodium 2-phenyl-monochloro-phenolate and 30 parts of sodium pentachlorophenolate was modified by the inclusion of 30 parts by weight of sodium 2,3,4,6-tetrachlorophenolate. This mixture of toxicant materials was tested according to the well known agar plate method to determine its efficiency against such common wood stainers and destroyers as *C. pillifera*, *H. gelatinosum*, and *L. trabea*. Sodium pentachlorophenolate alone was employed as a control material.

The phenolate mixture was found to completely inhibit and kill *C. pillifera* at a concentration of between 0.0035 and 0.005 per cent by weight. Sodium pentachlorophenolate inhibited and killed this organism at a concentration of between 0.005 and 0.007 per cent.

Against *H. gelatinosum*, the phenolate mixture gave complete inhibition and kill at between 0.0075 and 0.010 per cent. With sodium pentachlorophenolate, between 0.010 and 0.020 per cent was required to give inhibition of growth, and between 0.020 and 0.035 per cent to kill the organism.

Against *L. trabea*, the phenolate mixture gave total inhibition and kill at a concentration of between 0.001 and 0.002 per cent. With sodium pentachlorophenolate, the concentration required to give total inhibition was between 0.002 and 0.0035. A concentration of between 0.0035 and 0.005 was required to kill the organism with the sodium pentachlorophenolate alone.

The compositions as hereinbefore described comprise the mixture of phenolates as the principal active toxicant but may be modified by the addition of other toxicants, or wetting and

dispersing agents. For example, inorganic and organic mercurials, borax, dinitrophenols and their salts, and water-soluble salts of sulfuric acid derivatives of alcohols, phenols, aromatic hydrocarbons, etc. may be incorporated into the phenolate mixtures, if desired, provided only that such addition agents not enter into chemical reaction with the phenol salts.

I claim:

1. A fungicidal and bactericidal composition comprising as an active toxicant a mixture of the alkali metal salts of pentachlorophenol and of 2-phenyl-monochlorophenol.

15 2. A fungicidal and bactericidal composition comprising as an active toxicant a mixture of from 10 to 100 parts by weight of sodium 2-phenyl-monochloro-phenolate with 100 parts of sodium pentachlorophenolate.

20 3. A fungicidal and bactericidal composition comprising as an active toxicant a mixture of from 10 to 100 parts by weight of an alkali metal salt of 2-phenyl-monochlorophenol with 100 parts by weight of an alkali metal salt of pentachlorophenol.

25 4. A fungicidal and bactericidal composition comprising as an active toxicant a mixture of from 10 to 100 parts by weight of sodium 2-phenyl-monochloro-phenolate with 100 parts by weight of a mixture of sodium pentachlorophenolate and sodium tetrachlorophenolate.

30 5. A fungicidal and bactericidal composition comprising as an active toxicant a mixture of 80 parts by weight of sodium pentachlorophenolate and 40 parts of sodium 2-phenyl-monochlorophenolate.

DONALD K. BALLMAN.
